UNITED STATES PATENT OFFICE.

CHARLES H. LEMON, OF MILWAUKEE, WISCONSIN.

STEP.

SPECIFICATION forming part of Letters Patent No. 693,037, dated February 11, 1902.

Application filed July 17, 1901. Serial No. 68,595. (No model.)

To all whom it may concern:

Be it known that I, CHARLES H. LEMON, residing at Milwaukee, in the county of Milwaukee and State of Wisconsin, have invented a new and useful Improvement in Steps, of which the following is a description, reference being had to the accompanying drawings, which are a part of this specification.

My invention has relation to improvements in steps, being particularly useful as a vehicle-step, although not necessarily restricted to that application, inasmuch as it may be employed to advantage wherever a step may be required.

The primary object of the invention is to provide a simple and inexpensive construction which shall be a secure safeguard against the foot tripping or slipping on the step, which, as is well known, often results in a serious accident, particularly in the case of street-cars and cars of railroad-trains.

With the above primary object in view the invention consists of the devices and parts or their equivalents, as hereinafter set forth.

In the accompanying drawings, Figure 1 is a plan view of my improved step. Fig. 2 is a longitudinal sectional view, and Fig. 3 is a transverse sectional view.

Referring to the drawings, the numeral 4 indicates the bordering frame, which may be of any desirable form, but preferably of the substantially rectangular form shown. The corners of the outer side of this frame are preferably rounded, as shown in the drawings, and said frame has a substantial cross-area or width, and from its inner side and at a desired distance below its top edge extend therefrom horizontal flanges 5. These flanges are only necessarily required to extend from the outer and inner sides of the frame, but as a matter of convenience may be continued so as to extend inwardly also from the ends of the frame, as illustrated in the accompanying drawings, thereby making a continuous flange projecting from the inner faces of the four sides of the frame. Extending across the frame and having their ends resting upon the flanges of the front and rear portions of said frame are flat strips or plates 6. The upper edge of each of these plates is serrated or formed with a series of projections 7, preferably of rounded form. These serrations or

projections advisably project slightly above the plane of the top edge of the frame, forming a firm hold for the foot of a person mounting the step and greatly reducing the danger of slipping either transversely or longitudinally of the strips. These strips or plates are spaced apart by means of spacing blocks or washers 8. I prefer to make these washers 60 of globular or circular form, so as to prevent as much as possible the step becoming clogged up with accumulations or dirt, ice, snow, &c. Their rounded formation of course tends to cause the dirt or other accumulations to slip 65 thereoff, and they furthermore present but a minimum of surface upon which said dirt or accumulations can lodge. The flat plates and the interposed spacing-blocks are held firmly together by means of longitudinal tie-rods 9, 70 which rods pass through openings in the plates and registering openings in the spacing-blocks. The ends of these rods extend through the ends of the frame, and their extremities are threaded to receive thereon locking-nuts, 75 as shown. By turning these nuts it is evident that the parts can be tightly drawn together.

It may sometimes be found desirable to turn the spacing-blocks by hand in order to 80 loosen and dislodge any dirt which by any possibility may have accumulated on the blocks or which may have settled in the spaces between said blocks and the flat strips or plates. I therefore prefer that the openings of the 85 spacing-blocks through which the tie-rods pass be large enough to provide for this turning by application to the blocks of sufficient force to overcome the resistance offered by the clamping action thereagainst of the flat 90 strips or plates.

The spaces in many forms of open-work steps are so large as to admit the heel of a shoe therein, and experience has demonstrated that many of the most serious accidents, 95 especially in the case of street-cars, are due to this cause. In my invention I employ means for overcoming this serious disadvantage, and this consists in providing each of the spacing-blocks with an annular flange 10, 100 which extends around the block so as to lie in a vertical plane and about midway between two of the plates 6. It will be evident that these flanges so narrow the spaces between

the plates as to render it impossible for the heel or any part of the shoe to get into said spaces, and thereby cause the tripping of a person. I prefer that the upper edges of these flanges 5 shall be slightly below the upper edges of the serrations or projections 7. If said flanges extended upwardly flush with the upper edges of the projections referred to, the shoe of a person mounting the step would be likely to 10 come squarely in engagement with the flange and possibly result in turning the spacing-washer, and thereby produce a slipping and defeating the very object which it is the function of said flanges to accomplish. Where a 15 frame of the particular formation shown in the drawings is employed—that is to say, a frame provided with the rounded front corners—I prefer that the ends of the outermost or front tie-rod shall be bent downwardly and 20 through the flanges 5 rather than to extend through the rounded corners of the frame, as convenience in construction is thereby promoted.

In order to strengthen the frame, I prefer 25 to employ one or more brace-rods 11. These rods extend transversely of the frame, and their opposite ends are bent upwardly and pass through the flanges 5 from the under sides of the flanges and are upset upon the 30 upper sides of said flanges.

The parts of the complete step of course are 35 advisably made of strong metal, although any other desirable material may be employed, if preferred.

35 From the foregoing description it will be seen that I provide a most simple and cheap form of step well adapted for use generally, but especially adapted as a car or vehicle step and of such construction that the danger 40 of accident from slipping or tripping is reduced to the minimum.

What I claim as my invention is—

1. In a step, the combination of a frame 45 provided upon opposite inner sides with inwardly - extending horizontal flanges, flat plates or strips having their ends resting upon the opposite flanges, spacing blocks or washers between the plates, and means for securing the plates and the spacing-blocks together.

50 2. In a step, the combination of a frame provided upon opposite inner sides with inwardly - extending horizontal flanges, flat plates or strips having their ends resting upon the opposite flanges, spacing blocks or washers between the plates, and arranged on a 55 plane below the upper edges of the plates, and means for securing the plates and the spacing-blocks together.

3. In a step, the combination of a frame 60 provided upon opposite inner sides with inwardly - extending horizontal flanges, flat plates or strips having their ends resting upon the opposite flanges, the upper edges of said plates being roughened or serrated, spacing blocks or washers between the plates, and 65 means for securing the plates and the spacing-blocks together.

4. In a step, the combination of a frame provided upon opposite inner sides with inwardly - extending horizontal flanges, flat 70 plates or strips having their ends resting upon the opposite flanges, spacing blocks or washers between the plates, said blocks or washers being of circular form, and means for securing the plates and washers together. 75

5. In a step, the combination of a frame provided upon opposite inner sides with inwardly - extending horizontal flanges, flat 80 plates or strips having their ends resting upon the opposite flanges, spacing-blocks between the plates, and tie-rods passing through registering openings in the plates and blocks, and having their ends secured to the frame. 85

6. In a step, the combination of a frame provided upon opposite inner sides with inwardly - extending horizontal flanges, flat 90 plates or strips having their ends resting upon the opposite flanges, spacing-blocks between the plates, and means for adjustably clamping said plates and spacing-blocks together. 95

7. In a step, the combination of a frame provided upon opposite inner sides with inwardly - extending horizontal flanges, flat 100 plates or strips having their ends resting upon the opposite flanges, spacing-blocks between the plates, tie-rods passing through registering openings in the plates and blocks, and having their ends passing through the frame, and nuts on the threaded extremities of the rods and providing a means for adjustably 105 clamping the plates and interposed spacing-blocks together.

8. In a step, the combination of a frame provided upon opposite inner sides with inwardly - extending horizontal flanges, flat 110 plates or strips having their ends resting upon the opposite flanges, spacing-blocks between the plates, means for securing the plates and the washers together, and filling-pieces extending above the spacing-blocks, and narrowing the spaces between two of the plates. 115

9. In a step, the combination of a frame provided upon opposite inner sides with inwardly - extending horizontal flanges, flat 120 plates or strips having their ends resting upon the opposite flanges, turnable spacing-blocks between the plates, and means for holding the plates and spacing-blocks together. 125

10. In a step, the combination of a frame provided upon opposite inner sides with inwardly - extending horizontal flanges, flat 130 plates or strips having their ends resting upon the opposite flanges, spacing blocks or washers between the plates, and tie-rods passing through registering openings in the plates and blocks, and having their extremities secured to the frame, the spacing-blocks being mounted on the rods so as to be capable of turning thereon.

11. In a step, the combination of a frame 135 provided upon opposite inner sides with inwardly - extending horizontal flanges, flat plates or strips having their ends resting upon the opposite flanges, spacing blocks or wash-

ers between the plates, said blocks or washers being of circular form and provided each with a flange projecting outwardly therefrom and narrowing the space between two of the 5 plates, and means for securing the plates and the spacing-blocks together.

12. In a step, the combination of a frame provided upon opposite inner sides with inwardly - extending horizontal flanges, flat 10 plates or strips having their ends resting upon the opposite flanges, turnable spacing blocks or washers between the plates and provided

therearound with a projecting flange, said flange being disposed on a vertical plane and narrowing the space between two of the plates, 15 and means for securing the plates and the spacing-blocks together.

In testimony whereof I affix my signature in presence of two witnesses.

CHARLES H. LEMON.
